UNITED STATES PATENT OFFICE.

WILLIAM CARNAL, OF AKRON, OHIO, ASSIGNOR TO THE CAREY TIRE & RUBBER COMPANY, OF CAREY, OHIO, A CORPORATION OF OHIO.

DESIGN FOR A TIRE.

61,221.

Specification for Design.

Patented July 18, 1922.

Application filed September 8, 1920. Serial No. 409,004. Term of patent 14 years.

To all whom it may concern:

Be it known that I, WILLIAM CARNAL, a citizen of the United States, residing at Akron, in the county of Summit and State of Ohio, have invented a new, original, and ornamental Design for Tires, of which the following is a specification, reference being had to the accompanying drawing, forming a part hereof.

I claim:

The ornamental design for a tire as shown.

WILLIAM CARNAL.
